Henry G. Thompson of New York A. of Dec. 2130

Assignor to

The Hartford Carpet Company of Hartford, Ct.

Letters Patent No. 2130. Dated July 14, 1865

Design for a Carpet pattern

The schedule referred to in these Letters Patent, and making a part of the same

To all whom it may concern

Be it known that of Henry G. Thompson of the City, County and State of New York, have invented or produced a new and original Design for a Pattern to be wrought into two ply Drugrain and other Carpeting, in colors similar to those painted on the drawings accompanying this Specification, or in other colors substituted in the place of those painted on the drawings herewith; and I do hereby declare that the drawings accompanying this Specification, do give and convey to any one skilled in the art of Carpet weaving a more defined and thorough description of the nature of my invention than it is in the power of language otherwise. It however, will be sufficient to enable any one skilled in the art of Carpet weaving to use my invention.

What I claim as my invention and desire to secure by Letters Patent, is the configuration of the Design hereunto annexed, when made by being wrought into two ply Drugrain or other Carpeting, in the form similar to the drawings accompanying this Specification.
